UNITED STATES PATENT OFFICE.

CARL Z. ALEXANDER, OF WEST LIVINGSTON, AND EARL S. ALEXANDER, OF NEWARK,
NEW JERSEY, ASSIGNEES, BY MESNE ASSIGNMENTS, TO EDWIN C. SEWARD, OF
JERSEY CITY, NEW JERSEY.

BOILER-FEEDING APPARATUS.

Application filed February 27, 1922. Serial No. 539,427.

This invention relates especially to feeding apparatus for steam boilers of the general type covered by the Alexander Patent No. 1,240,804 of September 25, 1917 and described in greater detail in our pending application Serial No. 491,644, filed October 11, 1921. One or more geyser tubes may be cast integral with or formed within the fire box section of the boiler so as to automatically supply water to the upper heating surfaces or steam chambers of the boiler under operating conditions when the water flows over these plates in thin sheets or streams so that it can be evaporated under efficient conditions. With this type of boiler comparatively little water space is provided within the boiler and it is advantageous to have an equalizing water tank of considerable capacity mounted adjacent or around the boiler at about the normal water line thereof so as to furnish considerable additional water space. It is also of decided advantage to have a feed tank in which the drip return is received from the heating system and a connected feed pipe which preferably has a restricted inlet in the feed tank is adapted to feed this drip return water in a substantially continuous manner into one or more of the upper steam chambers of the boiler while in case of a sudden influx thereof into the feed tank an equalizing connection, preferably at a somewhat higher level in the feed tank may conduct this surplus water into the equalizing tank below. This equalizing tank, which may have any suitable shape and ample size for the particular boiler with which it is to be connected, may effectively serve as a settling tank since the drip return from the radiators or other devices using the steam may be led into one side or end of the equalizing tank which may have separating ribs extending up more or less from its bottom so as to form a series of settling or separating sections or chambers in which rust or other sediment collects near the drip return. The water supply connection for the boiler may be taken out of this equalizing tank adjacent the other end so that at least considerable sediment and impurities may be removed from the water before it is returned to the boiler. It is also advantageous in many cases to mount, in the general way disclosed in our copending application, Serial No. 520,005 of December

5, 1921, water heating coils or pipes within this equalizing tank near the boiler so as to heat the water used for domestic purposes as it flows through this heating coil within the equalizing tank which may, of course, be heavily lagged to prevent undesirable heat radiation therefrom.

In the accompanying drawing showing in a somewhat diagrammatic way an illustrative embodiment of this invention Figure 1 is a vertical section taken through the boiler. Figure 2 is an enlarged vertical section showing the boiler feeding apparatus.

Figure 3 is a top view of the equalizing tank and Figure 4 is a fragmentary sectional view, taken on the line 4-4 of Figure 2.

The boiler of this Alexander type may be of any suitable construction and may either be a vertical or round section boiler as indicated or a sectional boiler, if desired. The fire box section 1 is shown as being of water jacket construction so as to form a water space or water jacket 2 around the fire and a suitable geyser device may be installed adjacent the upper part of the fire box and may comprise water legs 23 cast with the fire box section and connected to a geyser tube 24 through which water is delivered automatically under operating conditions to the upper steam chamber 5. The water may then flow over a series of enclosed ribbed surfaces forming tortuous channels for the water which finally passes down through nipples or connections into the lower steam chamber 4 connected with the water jacket below by various nipples or connections 23'. The steam which is generated under efficient conditions in these steam chambers heated by the hot gases finally escaping through the smoke connection 6, is led off through suitable steam supply pipes such as 26 connected to the radiators or other steam utilizing devices operated by the boiler. The condensed water from the steam radiators or other devices in which the steam is used returns through suitable drip returns or pipes such as 31, for example, to which may be connected the feed tank 30 of cast iron or other suitable material and having any desired size and shape. This tank preferably has one or more separating partitions 32 formed on its bottom between the rear portion where the drip return 31 enters and the forward portion of this feed tank where

the boiler feed pipe 34 is arranged so as to have its small diameter or relatively small inlet opening 35 preferably projecting upward a short distance above the bottom of the tank. This feed pipe may be connected in any desired way with one or more of the upper steam chambers or upper heating surfaces of the boiler to which the water is to be fed and preferably has a water sealed portion such as at the lower end 38 of the main feed pipe section 37 which may project into a priming recess 39 formed as indicated in the upper steam chamber 5 adjacent the guiding partitions 40. Sufficient water is thus normally held in this recess so as to form a water seal for the feed pipe and substantially prevent entrance of steam into the pipe which is desirable for some purposes. It is also desirable to have a cleanout plug such as 36 detachably arranged in a T or coupling in the feed pipe so that by removing this plug the inlet opening can be cleared or inspected when necessary and the continued operation of the feed pipe ensured.

In some cases as where water collects in the steam radiators large amounts of water are occasionally fed down the drip return pipe and under these conditions it is preferable to discharge such surplus water or remove it from the feed tank so that a more constant feed of water can be maintained through the feed pipe to the upper heating surfaces of the boiler. For this purpose an equalizing connection such as 8 may be arranged in the feed tank and may have a relatively large inlet opening 33 preferably arranged somewhat above the feed pipe inlet 35 so that under such sudden flooding or feeding of water to the feed tank it may be quickly removed therefrom by this equalizing connection as soon as the water level in the feed tank rises above the equalizing inlet 33. This equalizing connection which may convey the drip return water in any desired way to the water space of the boiler preferably connects with an equalizing tank such as 11 having considerable capacity and located at about the normal or static water line of the boiler. As indicated in Figs. 1 and 3 this equalizing tank may be of curved form and more or less embracing the boiler and supported therefrom and connected thereto as through suitable nipple or pipe connections such as 7, 27 and the water supply connection 21 communicating with the water space at the lower part of the boiler. This equalizing tank which may have a gauge glass 16 mounted on the dome 9 to which the equalizing pipe is connected through the T connection 15 may have in some cases a series of separating partitions or ribs 22 extending upward from the bottom of the tank so as to catch and retain the sediment and dirt

which are often carried into the equalizing tank in considerable amounts by the sudden flooding of water into the same as above indicated. This sediment may be removed from time to time through the valved drain pipe 20 and the removable end plate 12 may also be taken off and the entire equalizing tank scraped or hosed out occasionally for cleaning purposes. By having the water supply pipe or connection 21 arranged at the opposite end 19 of the equalizing tank from the equalizing connection 8 therewith, this sediment is, of course, caught and deposited in the intermediate portions of the equalizing tank and is removed to a corresponding extent from the water which is supplied to the boiler through the pipe 21. If desired, water heating coils or pipes 44 may be mounted within this equalizing tank as shown in Figures 2 and 3, so as to heat water for domestic purposes, for example, when proper connection is made with the projecting portions 43 of these pipes.

While we have shown and described a certain preferred embodiment of the invention, it will be understood that this is primarily for the purpose of illustrating the principles of the invention, and that many modifications and changes may be made in the details of construction without departing from the spirit or scope of the invention. Therefore, we do not desire to be understood as limiting ourselves except as required by the following claims when construed in the light of the prior art.

We claim:

1. The steam boiler comprising a water jacket fire box section, one or more superimposed steam chambers having heating surfaces arranged above said fire box section and a geyser device connected to said fire box section and automatically supplying water therefrom to the upper heating surfaces in said steam chambers under operating conditions, an equalizing tank arranged adjacent said fire box section at about the normal water level therein and having a water supply connection with the water space at the lower part of the boiler, a feed tank to be connected to the drip return of the boiler, a feed pipe having an inlet in the lower part of said feed tank, a cleanout plug in said feed pipe to clear its inlet and a water seal recess in the upper steam chamber of the boiler with which the depending end of said feed pipe communicates to feed the drip return water to the upper heating surfaces of said boiler, and an equalizing connection communicating with said equalizing tank and having a relatively large inlet end in said feed tank at a higher lever than the feed pipe inlet therein.

2. The steam boiler comprising a water jacket fire box section, one or more superimposed steam chambers having heating sur-

- faces arranged above said fire box section and a geyser device connected to said fire box section and automatically supplying water therefrom to the upper heating surfaces in said steam chambers under operating conditions, a feed tank to be connected to the drip return of the boiler, a feed pipe having an inlet in the lower part of said feed tank, and a water seal recess in the upper 5 steam chamber of the boiler with which the depending end of said feed pipe communicates to feed the drip return water to the upper heating surfaces of said boiler, and an equalizing connection communicating 10 with a lower water space of the boiler and having a relatively large inlet end in said feed tank at a higher level than the feed pipe inlet therein.
3. The steam boiler comprising a fire box 20 section, one or more superimposed steam chambers arranged above said fire box section and a geyser device connected to said fire box section and automatically supplying water therefrom to the upper heating surfaces in said steam chambers under operating conditions, a feed tank to be connected to the drip return of the boiler and having a separating partition, a feed pipe having a water seal device and an inlet in the lower 25 part of said feed tank on the other side of said partition from the drip return connection to feed the drip return water to the upper heating surfaces of said boiler and maintain a water seal in said feed pipe, and 30 an equalizing connection communicating with the water space at the lower part of the boiler and having a relatively large inlet end in said feed tank at a higher level than the feed pipe inlet therein.
4. The steam boiler comprising a fire box 40 section, one or more superimposed steam chambers arranged above said fire box section and a geyser device connected to said fire box section and automatically supplying water therefrom to the upper heating surfaces in said steam chambers under operating conditions, a feed tank to be connected to the drip return of the boiler and a feed pipe having a water seal device and an inlet in 45 said feed tank to feed the drip return to the upper heating surfaces of said boiler and maintain a water seal in said feed pipe, and an equalizing connection communicating with the water space at the lower part of 50 the boiler and having a relatively large inlet end in said feed tank.
5. The steam boiler comprising a fire box 60 section, one or more superimposed steam chambers arranged above said fire box section and a geyser device connected to said fire box section and automatically supplying water therefrom to the upper heating surfaces in said steam chambers under operating conditions, a feed tank to be connected to 65 the drip return of the boiler and a feed pipe having an inlet in said feed tank to feed the drip return water to the upper heating surfaces of said boiler, and an equalizing connection communicating with the water space at the lower part of the boiler and having a relatively large inlet end in said feed tank.
6. A steam boiler comprising a fire box, a water chamber, one or more superimposed steam generating surfaces arranged above said fire box, means for feeding water from 70 said water chamber to said steam generating surfaces, a drip return water feed tank, a feed pipe having a small inlet in said tank for delivering water from said feed tank to said steam generating surfaces, and an equalizing connection having a relatively large inlet in said feed tank at a higher level than the feed pipe inlet therein and communicating 75 with said water chamber of the boiler.
7. The feeding apparatus for a steam 80 boiler having a lower fire box water space and upper heating surfaces receiving water therefrom, comprising a feed tank to be connected to the drip return of the boiler, a feed pipe having an inlet in the lower 85 part of said feed tank and a water seal recess adjacent the upper heating surfaces of the boiler with which the depending end of said feed pipe communicates to feed the drip return water directly to said upper 90 heating surfaces and maintain a water seal at the discharge end of said feed pipe and an equalizing connection having a relatively large inlet end in said feed tank at a higher 95 level than the feed pipe inlet therein and communicating with a lower water space 100 of the boiler.
8. The feeding apparatus for a steam boiler having a lower fire box water space and upper heating surfaces receiving water 105 therefrom, comprising a feed pipe to be connected to the drip return of the boiler to feed the drip return water directly to said upper heating surfaces and a relatively large capacity emergency connection delivering 110 drip return water to said lower fire box water space without passing through said feed pipe.
9. A steam boiler comprising a fire box, a water chamber, one or more superimposed 115 steam generating surfaces arranged above said fire box, means for feeding water from said water chamber to said steam generating surfaces, a drip return water feed tank, a feed pipe having a small inlet in said tank 120 for delivering water from said feed tank to said steam generating surfaces, an equalizing tank arranged adjacent the boiler and having a connection with a relatively large inlet in said feed tank at a higher elevation 125 than said feed pipe inlet therein to receive water from said feed tank, and a connection between said equalizing tank and said water chamber of said boiler.
10. The combination with a steam boiler 130

having small water capacity and a steam generating surface above the water level, of a drip return water feed tank, a feed pipe for delivering water from said feed tank to 5 said steam generating surface, a relatively large equalizing tank partially surrounding said boiler closely adjacent thereto to receive heat therefrom, said tank being horizontally disposed at the normal water level 10 of the boiler, a boiler drip return connection leading from said feed tank to one end of said equalizing tank, a connection adjacent the other end of said equalizing tank to supply water therefrom to the boiler, and 15 heating coil pipes within said equalizing tank for heating water passing through said pipes for domestic purposes.

11. A steam boiler equalizing and water heating tank, adapted for use with a steam boiler having relatively small water capac- 20

ity, comprising an equalizing tank adapted to partially surround and be arranged closely adjacent the fire box section of the boiler at the normal water level thereof and having adjacent one end a boiler drip return connection, a water supply connection adjacent the other end of said equalizing tank to supply water to said boiler, a series of separating ribs extending upward from the bottom of said equalizing tank to form 25 a series of separating compartments in said tank and promote the separation of sediment in the sections of said tank adjacent said drip return, and heating coil pipes arranged within said equalizing tank and 30 adapted to heat water passing through said pipes for domestic purposes.
